UNITED STATES PATENT OFFICE.

ALBERT D. JUDD, OF NEW HAVEN, CONNECTICUT.

DESIGN FOR A BRACKET.

Specification forming part of Design No. **6,686**, dated May 27, 1873; application filed May 20, 1873.

To all whom it may concern:

Be it known that I, ALBERT D. JUDD, of New Haven, in the State of Connecticut, have invented a Design for a Bracket, of which the following is a specification:

The nature of the said design is fully represented in the accompanying perspective view.

The wall-plate *a* is made of the ornamental outline or configuration shown, and its surface is recessed, leaving the leaf and scroll-work in relief with a central flat surface for the socket *b*. The arm or bracket that is upon the pintle *c* is of the ornamental curved shape shown at *e*, forming the principal portion of such bracket, with the scroll and leaf ornaments *f g h* above it, and the ornaments *k l* below it, and the surface of the bracket *e* is ornamented as shown, and at the end thereof are the bands or collars *m*, and above them the bands or collars *n o* of the ornamental arms *p* and *q*, that are of the shape and are

ornamented as represented. The dish or holder *s* has a beveled edge and an inverted central dome, *t*, with the lozenge-shaped ornaments around the edge of such holder *s*.

I claim as my invention—

1. The design of the shape and ornamentation of the wall-plate *a* and socket *b*, as shown.
2. The design of the shape and ornamentation of the bracket-arm *e f g h k l*, as represented.
3. The design of the shape and ornamentation of the arm *p* or *q*, as represented.
4. The design of the shape and ornamentation of the holder *s t*, as represented.

Signed by me this 12th day of May, A. D. 1873.

A. D. JUDD.
